UNITED STATES PATENT OFFICE.

LOUIS L. SCHACHT, OF NEW YORK, N. Y.

FLASHLIGHT-TORCH.

1,389,702.

Specification of Letters Patent. Patented Sept. 6, 1921.

Application filed March 17, 1920. Serial No. 366,602.

To all whom it may concern:

Be it known that I, LOUIS L. SCHACHT, a citizen of the United States, and resident of the borough of Bronx, county of Bronx, and city and State of New York, have invented certain new and useful Improvements in Flashlight-Torches, of which the following is a description.

The present invention relates to improvements in flash light torches, especially for photographic use, and has for an object to provide a device of this character adapted to produce a powerful sustained light, and which will be compact and safe, and convenient to operate. Such apparatus heretofore employed for this purpose was cumbersome, complicated and attendant with considerable risk due to the uncertain manner in which the fuel is controlled.

I propose in the present invention, to provide a device capable of being carried in the pocket of the photographer which may be safely operated by the man taking a photograph, and with which a sustained, uniform and powerful light may be produced. I further propose to provide a novel arrangement for supplying the magnesium or other fuel material, and in which the combustion of the material will be complete to the end that a better light will be produced and danger from particles of partially burnt fuel dropping is obviated.

A further object is to provide a device in which the handle and the fuel containing chamber provided therein will be protected from the effects of the heat produced by the light.

With this and other objects in view, an embodiment of my invention is shown in the accompanying drawings, and this embodiment will be hereinafter more fully described with reference thereto, and the invention will be finally pointed out in the claims.

In the accompanying drawings:

Figure 1 is a side elevation of the device according to the present embodiment of my invention.

Fig. 2 is a vertical sectional view thereof.

Fig. 3 is a plan view, and,

Fig. 4 shows the manner in which the device is held and operated by the photographer.

Similar reference characters indicate corresponding parts throughout the several views of the drawings.

Referring to the drawings, and more particularly to Figs. 1 and 2 thereof, an embodiment of my invention shown therein comprises a tubular casing 10 of convenient length, to be comfortably held in the hand of the operator, and provided interiorly substantially centrally thereof with a lateral partition plate 11 dividing the casing into an upper and a lower compartment. The ends of the casing are screw-threaded, and are engaged by a top cap 12 and a bottom cap 13.

A blow pipe tube 14 extends into the upper portion of the upper compartment, and downwardly along the side thereof, being deflected at its lower end, as at 15, so that it is directed substantially toward the center of the partition plate 11.

Upon the upper side of the cap 12 there is provided a post 16, to which there is secured by means of a screw 17, a bracket 18, supporting at its looped ends 19 and 20 a ring 21 formed of woven asbestos fiber, this ring being substantially spaced by the bracket from the upper end of the casing. A plurality of vertical upwardly projecting tubes 22 are provided in the cap 12, radially surrounding the post 16, and terminating slightly below the ring 21, these tubes being in communication with the interior of the upper compartment of the casing.

The operation of the device is as follows:

The upper compartment is partially filled with powdered magnesium or other suitable combustible material. Within the lower compartment there is provided a bottle 23, containing alcohol or other suitable liquid fuel, with which the asbestos ring 21 is primarily saturated. A flexible tube 24 is connected to the exteriorly projecting end of the tube 14, and by blowing through this tube, as indicated in Fig. 4, the current of air is produced within the compartment 10 rising from the bottom 11 along the sides, and carrying the magnesium upwardly through the tubes 22, where it burns in the flame of the torch which has previously been lighted, producing a powerful and sustained light, which may be controlled, as to brilliancy and uniformity, by the operator blowing through the tube. The spacing of the ring 21 above the casing by the bracket 18, which is preferably of a heat resisting material from the casing, prevents the casing from becoming heated by the flame, so that

danger of the supply of magnesium contained in the casing becoming overheated and burning, is prevented. The injection of the magnesium upwardly into the center 5 of the flame within the ring 21 insures a thorough combustion of the same without danger of the particles dropping downwardly upon the hand of the operator and burning him, and results in a thorough 10 mingling of the material into the flame being drawn by the force of the air into cone shape. The several outlets of small gage regulate and distribute the pressure, so that a too forceful blast of air into the flame will 15 be prevented. Furthermore, a light is produced, having a maximum illuminating efficiency. The device, as will be seen, is very compact, and may be readily carried within the pocket of the photographer, and 20 he may conveniently operate the same with the use of one hand.

The device will prove efficacious in taking 25 photographs under the most exacting circumstances, as a sustained light of great brilliancy may be produced and accurately controlled at all times by the photographer.

The interior of the lower compartment is 30 preferably covered with a protective lining of blotting paper or the like to protect the bottle contained therein, and prevent it from rattling.

I claim:

1. An improved flash light torch comprising a holder for powdered material providing 35 a handle, a blow pipe tube extending into the holder near its upper end and projecting downwardly opening into the holder near its base, a ring of absorbent material extending in spaced relation above the upper 40 end of the holder and being concentric with the projected axis of such holder, and a plurality of tubes extending from the upper portion of the holder upwardly toward said ring and having their upper ends spaced below the ring.

2. An improved flash light torch comprising a holder for a powdered substance also providing a handle, a blow pipe tube extending into the holder near its upper end 50 and lying in close proximity to the wall of the holder, said tube near its lower end being flared toward the central part of the holder, a ring of absorbent non-combustible material supported in spaced relation above the 55 upper end of the holder and being concentric

with the projected axis of the holder, and a plurality of tubes leading upwardly from the upper end of the holder and being also concentric of the axis of the holder, said tubes having their lower ends spaced below 60 said ring.

3. An improved flash light torch comprising a holder of elongated construction provided with a partition therein forming a chamber above the partition for containing a 65 powdered combustible substance, said holder forming a handle to support the torch, means extending into proximity with the bottom of the chamber for introducing a blast thereto, a top for the holder, a bracket 70 supported on said top, an annulus of absorbent non-combustible material supported in said bracket substantially concentric with the projected axis of said holder, a plurality of tubes extending through the top of the 75 holder and lying about said bracket, the lower portion of the holder beneath said partition forming a compartment to receive a container for material used to saturate said non-combustible ring, and a removable bottom for the holder.

4. An improved flash light torch comprising a holder for powdered substance, a cap thereon, a post on the cap, a bracket fixed to the post and having upwardly disposed 85 arms, a ring of non-combustible material supported in said arms, tubes projecting upwardly through said cap, and means to deliver a blast of air into the holder.

5. An improved flash light torch comprising a holder for powdered combustible material and also providing a handle at its lower portion, means connecting with the upper portion of the holder for delivering a blast of air to the powdered material, a ring 95 of absorbent non-combustible material supported above the holder and substantially concentric with the projected axis of the holder, and means communicating with the upper portion of the holder for delivering 100 a plurality of minute jets of the powdered combustible material upwardly through the space confined by the ring, said last named means being spaced below the ring to provide an air space therebetween.

In testimony, that I claim the foregoing as my invention, I have signed my name hereunder.

LOUIS L. SCHACHT.
